UNITED STATES PATENT OFFICE.

HENRY F. SAWTELLE, OF LEOMINSTER, MASSACHUSETTS.

FIRE-EXTINGUISHER.

No. 861,320.

Specification of Letters Patent.

Patented July 30, 1907.

Application filed March 6, 1907. Serial No. 360,848.

To all whom it may concern:

Be it known that I, HENRY F. SAWTELLE, a citizen of the United States of America, and a resident of Leominster, in the county of Worcester and State of Massachusetts, have invented certain new and useful Improvements in Fire-Extinguishers, of which the following is a specification.

This invention relates to fire extinguishers and particularly to fire extinguishers which are adapted for use on railway cars or similar vehicles and has for its object the production of an extinguisher which may be secured to the frame of the vehicle and be accessible for use after an accident has occurred in whatever position the car may be in.

15 The invention consists in certain novel features of construction and arrangement of parts which will be readily understood by reference to the description of the drawings and to the claims hereinafter given.

20 Of the drawings: Figure 1 represents a side elevation of a portion of a car showing the preferred location of the fire extinguisher embodying the features of this invention. Fig. 2 represents a transverse section of the same looking toward the end of the car and showing an extinguisher embodying the features of this 25 invention secured to the under side of the framework. Fig. 3 represents an elevation, partly in section, of the extinguisher, drawn to an enlarged scale. Fig. 4 represents a plan, partly in section, of the same. Fig. 5 represents an end view of the same. Fig. 6 represents a section on line 6-6 on Fig. 3, looking in the direction of the arrow. Fig. 7 represents a transverse section on line 7-7 on Fig. 3, looking in the direction of the arrow. Fig. 8 represents a section on line 8-8 on Fig. 5, looking in the direction of the arrow, and 30 drawn to a larger scale. Fig. 9 represents a horizontal section on line 9-9 on Fig. 8. Fig. 10 represents an enlarged section of a portion of the acid-receptacle breaking device. Fig. 11 represents a section of the acid-receptacle, and Fig. 12 represents a section showing the means of securing the longitudinal pipes to the main tank.

Similar characters designate like parts throughout the several figures of the drawings.

In the drawings, 10 represents a car of any suitable 45 construction mounted upon any desired truck 11. From the bottom of the frame 12 at either side of the car depends the bracket 13 in which is mounted a cylindrical tank 14 extending transversely of said car, said tank being prevented from end movement by 50 means of the flanges 15 abutting said brackets 13. Each end of the tank 14 is provided with an extension 16 in which is mounted an acid-receptacle 17 which is positioned in said extension by means of a plurality of inwardly-extending lugs from the inner walls of 55 said extension and a collar 18 threaded to the open end thereof. The receptacle 17, by these various

lugs and the collar 18, is held firmly in position and prevented from being displaced during the movement of the car to which the fire extinguisher may be attached. The receptacle 17 is preferably of glass 60 and is provided with an annular channel 19 cut into the periphery thereof near one end for the purpose of weakening the receptacle so that it will break at this point when an accident occurs to permit the acid to escape into the interior of the tank 14 and mix 65 with the contents thereof to create sufficient gas therein to force out the liquids contained within said tank as will be hereinafter described.

Secured to the extension 16 are a plurality of bosses 20 in which is mounted a pointed pin 21 the point of 70 which engages with the bottom of the annular groove 19 in the receptacle 17. Said pin 21 is prevented from displacement by means of the perforated plate 22 secured to the outer end of said boss 20, the perforations 23 therein providing a ready means whereby 75 a nail or other member may engage with the rear end of said pointed pin 21 and be driven thereby into contact with the acid-receptacle 17 for the purpose of effecting a breakage thereof. I side the heads of the tank 14 at each end is an annular pipe 24 connected by a plurality of pipes 25 which are supported midway of their length by the Ts 26 secured to the casing 14 by means of the threaded shank 27 and nuts 28. These pipes 24 and 25 are all connected so that the contents of the tank are free to move freely 80 therethrough and one of the Ts 26 is provided with an additional branch 29 to which is connected a tube 30 the opposite end of which is provided with a hollow bulb-shaped weighted strainer end 31. This strainer end 31 is adapted to seek the bottom of the tank 14 90 in whatever position it may take and in order to provide for this the tube 30 is either made flexible throughout its length or at that point where it is connected to the branch 29.

Each of the annular pipes 24 is provided with a plurality of outwardly extending bosses 32 to which is 95 threaded the valve casing 33 the inner end of which is provided with a perforated conical end 34 in which is normally seated a valve 35 held to its seat by the spring 36.

The outer end of the member 33 has threaded thereto a member 37 by turning which the valve 35 may be removed from its seat to permit the passage of the liquid contained in the tank 14 through the perforated end 34 and through the discharge outlet 38, said discharge outlet extending through a threaded boss 39 to which any ordinary hose may be connected, this hose being normally kept in a compartment 40 secured to the under side of the frame of the car adjacent to the tank 14. This receptacle 40 is provided with a door on either side 105 of the car so that the hose is accessible in whatever position the car may be in after an accident has occurred.

In the outer face of each extension 15 is mounted a gage 41 which indicates the pressure within the tank 14 at all times.

In the operation of the device the tanks are preferably 5 secured directly under the bottom of the frame of the car but it is obvious that if so desired they may be placed elsewhere. The tanks may be filled with a non-freezing liquid or it is obvious that any other desired means may be taken to prevent the contents from freezing 10 in severe weather. The mixture with which the tank 14 is filled is of such a nature that when acid is mixed therewith a gas will be generated of sufficient strength to force the liquid contained therein through the perforations in the weighted strainer end 31 and 15 through the pipe or tube 30 into the pipes 25 from which they will pass through the valve casing 32 and out through the outlet 38 into the hose which may be coupled thereto. It is obvious, however, that this operation does not commence until the receptacle 17 containing 20 the acids has been broken either by means of the jar due to the accident or by having the receptacle positively broken by means of the breaking pin 21 being driven sharply into contact with the weakened portion 19 of said receptacle. Even when this occurs the liquid 25 will not be able to escape through the discharge outlet 38 owing to the action of the valve 35 until this valve 35 has been opened by the operation of the threaded member 37 thereon.

The tank is designed with the acid-receptacles at 30 either end so that no matter in what position the car may be after an accident has occurred at least one end thereof will be accessible so that a passenger or train hand could break the receptacle more conveniently and allow the contents to mix with the contents of the tank 35 for the purpose of producing the fire extinguishing mixture. In a similar manner the outlet valve casings are situated so that a hose may be easily coupled to one or the other of these discharge nozzles 39 no matter in what position the car may be. It is also obvious that the 40 flexible tube 30 is of such a length that the weighted strainer end thereof seeking its lowest level will reach the bottom of the tank whatever may be its position so that the liquid contained within said tank will be forced therethrough by the gases collected therein and these 45 liquids will be forced through the pipes onto the fire to extinguish the same.

This makes a very desirable fire extinguisher, particularly adapted for use in connection with moving vehicles and especially railway cars, it being obvious that 50 from an inspection of the drawings and from the description herein given that no matter what may be the position of the vehicle after an accident has occurred a hose may be readily coupled to at least one of its coupling nozzles and the valve readily operated to permit the 55 contents to flow through its outlet into the hose for use in extinguishing any fire which may have been ignited by such accident. It is obvious that provision is also made whereby the acid-receptacle is firmly positioned so that it is unlikely to breakage during the ordinary 60 movement of the vehicle to which said extinguisher may be attached, while it may be readily broken by the jar caused by the accident to place the fire extinguisher in commission. If such breakage does not occur from the jar caused by the accident provision is made where- 65 by the receptacle may be positively broken by a train

hand or other person with the simplest implements at hand.

It is believed that from the foregoing the operation of the invention and its many advantages will be fully apparent without further description.

Having thus described my invention, I claim:

1. In a fire extinguisher for vehicles, the combination of a tank secured to the outside of the frame of the vehicle and containing a solution; an acid-receptacle at either end thereof; means for effecting a mixture of said acid and solution; a movable tube within said tank provided with a free weighted end adapted to rest on the bottom of said tank; and a pipe connected to the opposite end of said movable tube adapted to provide an outlet 75 from said tank.

2. In a fire extinguisher for vehicles, the combination of a tank secured to the outside of the frame of the vehicle and containing a solution; an acid-receptacle at either end thereof; means for effecting a mixture of said acid and solution; a movable tube within said tank provided with a free weighted strainer end adapted to rest on the bottom of said tank; and a pipe connected to the opposite end of said movable tube adapted to provide an outlet from said tank.

3. In a fire extinguisher for vehicles, the combination of a tank secured to the outside of the frame of the vehicle and containing a solution; an acid-receptacle at either end thereof; means for effecting a mixture of said acid and solution; a movable tube within said tank provided with a free weighted strainer end; a pipe connected to the opposite end of said movable tube; an annular pipe at each end of said tank connecting with said pipe and provided with branches through the heads of said tank; and means for coupling a hose to either of said branches.

4. In a fire extinguisher for vehicles, the combination of a tank secured to the outside of the frame of the vehicle and containing a solution; an acid-receptacle at either end thereof; means for effecting a mixture of said acid and solution; a flexible tube within said tank provided with a free weighted end; a pipe connected to the opposite end of said flexible tube adapted to provide an outlet from said tank; an annular pipe at each end of said tank connecting with said pipe and provided with valved branches through the heads of said tank; and means for coupling a hose to either of said branches.

5. In a fire extinguisher for vehicles, the combination of a tank secured to the outside of the frame of the vehicle and containing a solution; an acid-receptacle at either end thereof; means for effecting a mixture of said acid and solution; a flexible tube within said tank provided with a free weighted end; a pipe connected to the opposite end of said flexible tube adapted to provide an outlet from said tank; an annular pipe at each end of said tank connecting with said pipe and provided with branches through the heads of said tank; a valve in each branch; and means for opening said valve.

6. In a fire extinguisher for vehicles, the combination of a solution-containing tank secured to the under side of the frame of the vehicle and extending from side to side thereof; an acid-receptacle at either end thereof; and means secured to said tank for breaking said receptacle.

7. In a fire extinguisher for vehicles, the combination of a tank secured to the under side of the frame of the vehicle and containing a solution; an acid-receptacle at either end thereof; means for effecting a mixture of said acid and solution; an annular pipe at each end of said tank; a plurality of pipes extending longitudinally of said tank and communicating with said annular pipes; a flexible tube connected to one of said pipes and extending to the bottom of the tank; and hose connections for each of said annular pipes.

8. In a fire extinguisher for vehicles, the combination of a tank secured to the under side of the frame of the vehicle and containing a solution; an acid-receptacle at either end thereof; means for effecting a mixture of said acid and solution; an annular pipe at each end of said tank; a plurality of pipes extending longitudinally of said tank and communicating with said annular pipes; a flexible tube connected to one of said pipes and extending to

the bottom of the tank; and a hollow perforated bulb secured to the free end of said flexible pipe.

9. In a fire extinguisher for vehicles, the combination of a tank secured to the under side of the frame of the vehicle and containing a solution; an acid-receptacle at either end thereof; means for effecting a mixture of said acid and solution; an annular pipe at each end of said tank; a plurality of pipes extending longitudinally of said tank and communicating with said annular pipes; a flexible tube connected to one of said pipes and extending to the bottom of the tank; and a hollow weighted member secured to the free end of said flexible tube.

10. In a fire extinguisher, the combination of a tank containing a solution; an acid-receptacle contained therein; means for effecting a mixture of said acid and solution; an annular pipe at each end of said tank; a plurality of pipes extending longitudinally of said tank and communicating with said annular pipes; a flexible tube connected to one of said pipes and extending to the bottom of the tank; and a hose connection for each of said annular pipes.

11. In a fire extinguisher, the combination of a tank containing a solution; an acid-receptacle contained therein; means for effecting a mixture of said acid and solution; an annular pipe at each end of said tank; a plurality of pipes extending longitudinally of said tank and communicating with said annular pipes; a flexible tube connected to one of said pipes and extending to the bottom of the tank; and a hollow perforated bulb secured to the free end of said flexible pipe.

12. In a fire extinguisher, the combination of a tank containing a liquid; a breakable receptacle therein adapted to contain chemicals; means for breaking said receptacle; a system of piping within said tank and extending through the wall thereof; a hose connection on an outer end of said pipe system; and a tube within said tank connected to the system of pipes, the free end of which is adapted to move to all parts of said tank.

13. In a fire extinguisher for vehicles, the combination of a tank secured to the outside of the frame of the vehicle and containing a solution; an acid-receptacle at one end thereof; means for effecting a mixture of said acid and solution; a flexible tube within said tank the free end of which is adapted to rest on the bottom of the tank; a pipe connected to the opposite end of said flexible tube and extending through the wall of said tank; and means for securing to the end of said pipe a suitable hose.

14. In a fire extinguisher for vehicles, the combination of a tank secured to the outside of the frame of the vehicle and containing a solution; an acid-receptacle at one end thereof; means for effecting a mixture of said acid and solution; a flexible tube within said tank the free end of which is provided with a weight which is adapted to rest on the bottom of the tank in any position which it may assume; a pipe connected to the opposite end of said flexible tube and extending through the wall of said tank; and means for securing to the end of said pipe a suitable hose.

15. In a fire extinguisher for vehicles, the combination of a tank secured to the outside of the frame of the vehicle and containing a solution; an acid-receptacle at one end thereof; means for effecting a mixture of said acid and solution; a flexible tube within said tank the free end of which is adapted to rest on the bottom of the tank; a pipe connected to the opposite end of said flexible tube and extending through the wall of said tank; a valve in the outer end of said pipe; and means for securing to the end of said pipe a suitable hose.

16. In a fire extinguisher for vehicles, the combination of a tank secured to the outside of the frame of the vehicle and containing a solution; a glass acid-receptacle at an end of said tank provided with a deep groove therein; and a movable member co-acting with said groove adapted to break said receptacle by impact therewith.

17. In a fire extinguisher, the combination of a tank containing a liquid; a receptacle therein adapted to contain chemicals; means for effecting a mixture of said liquid and chemicals; a system of piping within said tank and extending through the wall thereof; a hose connection on an outer end of said pipe system; and a tube within said tank connected to the system of pipes, the free end of which is adapted to move to all parts of said tank.

18. In a fire extinguisher, the combination of a tank containing a liquid; a receptacle therein containing a material adapted to effect a pressure within said tank upon escape; means for effecting the escape into said tank of said material; a system of piping within said tank and extending through the wall thereof; a hose connection on an outer end of said pipe system; and a tube within said tank connected to said system of pipes, the free end of which is adapted to move to all parts of said tank.

19. In a fire extinguisher, the combination of a tank containing a liquid; means for effecting a pressure within said tank; a system of piping within said tank and extending through the wall thereof; a hose connection on an outer end of said pipe system; and a tube within said tank connected to said system of pipes, the free end of which is adapted to move to all parts of said tank.

20. In a fire extinguisher, the combination of a tank containing a liquid; a receptacle connected thereto containing a material adapted to effect a pressure within said tank upon admission thereto; means for admitting the contents of said receptacle into said tank; a system of piping within said tank and extending through the walls thereof; a hose connection on an outer end of said pipe system; and a tube within said tank connected to said system of pipes, the free end of which is adapted to move to all parts of said tank.

Signed by me at Boston, Mass., this 2d day of March, 1907.

HENRY F. SAWTELLE.
